UNITED STATES PATENT OFFICE.

JOSEPH H. TAYLOR, OF TUXEDO, MARYLAND.

APPARATUS FOR AND ART OF STRAIGHTENING TYPE PLATES.

Application filed February 15, 1926. Serial No. 38,495.

These inventions relate to improvements in the art or process of preparing printing plates for the press and to apparatus well adapted for the practicing of the art.

5 The primary object in view is the effective straightening or correcting of the type face of printing plates in a ready, rapid and inexpensive manner.

10 A more detail object is the substantially complete obviating of hand straightening.

A still further object is the exertion of 15 stresses on the back face of the plate resiliently at a series of points spaced apart but sufficiently close together for exerting straightening stresses at substantially all 20 places on the back of the plate directly opposite places on the type face requiring straightening.

With these and further objects in view, 25 the invention comprises certain novel steps and combinations of steps of an art or process for straightening the type face of printing plates, and certain novel constructions, combinations and arrangements of parts of apparatus well adapted for carrying out the 30 art or process as will hereinafter in part be stated and in part become apparent.

In the accompanying drawings,—

Figure 1 is a vertical section through a 35 fragment of a structure well adapted for facilitating the carrying out of the art or process, the parts being shown in the position of the step of first subjecting the plate to pressure.

Figure 2 is a similar view of the same with the parts in the position of the completion of the step of complete straightening of the type face and just prior to the step of releasing the pressure.

40 Figures 3, 4 and 5 are, respectively, fragmentary top plan, side, and end views of a fragmentary part of the spring cushion utilized in and forming part of the present invention, the parts being seen on a magnified scale.

45 Figures 6 and 7 are views similar, respectively, to Figures 1 and 2 slightly modified by the addition of instrumentalities for indicating movement of parts.

50 Figures 8, 9 and 10 are views similar, respectively, to Figures 3, 4 and 5 of a slightly modified embodiment of the spring cushion.

Figure 11 is an end view of a slightly modified form of coil spring well adapted for use in the making of a spring cushion, 55 the parts being seen on a magnified scale.

Figure 12 is a similar view of a further modification of the same.

In the industrial art to which the present inventions relate, it has been the common 60 practice to straighten the type face of type plates, such as electrotypes, by placing the plates face down on a smooth surface and tapping the back of the plate by manually operated instruments. It has been proposed 65 to improve this manual method by placing the type plate with its face against a heating instrument having a flat surface and subjecting the back to pressure sufficient to cause the face to straighten when the heat 70 has penetrated the type metal sufficiently. To accomplish this result, it has been proposed heretofore to utilize a rubber blanket placed against the back of the type plate and subjected to pressure exerted toward the face 75 of the type plate. Other apparatus proposed has included hydraulic or pneumatic pressure devices stressing the back of the type plate in a direction toward the face thereof while the face is subjected to heat. 80

All of these devices have been successful in greater or less degree in straightening some or most of the larger irregularities of the type face, but lack of independent and individual responsiveness of different points at 85 the back of the type face has rendered it thus far impossible to straighten the type face completely, or even approximately completely, so that up to the present the straightening machines proposed have left in every instance the type plate in a condition requiring at least some manual straightening, and in many instances the manual work remaining to be done ranges from fifty to seventy-five per centum of the total straightening 90 necessary.

It has also been proposed to subject the type plate whose face is to be straightened to a straightening pressure delivered to the back of the plate by a series of plungers, 100 spring stressed or cushion stressed, but this proposal has not been found entirely satisfactory because of the impracticability of sufficiently close juxtaposition of the plung-

ers, and the results obtained by this last form of proposed construction have not been successful.

The present inventions have been demonstrated repeatedly as fully overcoming all of the difficulties experienced with all of the previously proposed methods and apparatus as above set forth, and by the utilization of the present inventions it has been found possible, in practically every instance, to straighten the type face substantially as perfectly as if it had been done by hand, and thus all handwork, or substantially all handwork, in the straightening of the type face is obviated incident to the present inventions.

It is, of course, well understood in this art that all type plates formed by the casting of type metal into a type shell when first cast are invariably irregular, and it is necessary, therefore, to straighten the face of such plates by the exertion of pressure at the back, which brings the irregularities to the back, and the back is afterwards planed and shaped for the press. In the accompanying drawings, the structures have been illustrated with certain exaggerated proportions for the purpose of facilitating ease of disclosure. For example the type plate is shown as possessing considerably greater thickness than the average type plate, and the type itself is illustrated as of greater depth than customarily employed. Also, the irregularities of the type face have been somewhat exaggerated, all for the purpose of making clear to the observer easily and quickly upon inspecting the drawings, the object, purpose and result of the present inventions. Accordingly, it will be understood that the inventions are applicable to type plates of any character, thickness and proportions which require straightening of their faces and which are susceptible of responding to the softening effect of heat.

Since a ready understanding of the art or process may be more quickly afforded by concrete illustration in referring to the structures in the accompanying drawings, said structures will be specifically described and the process set forth in the statement of the preferred operation of such structures.

Referring to the drawings by numerals, 1 indicates a gas heater or other appropriate hot plate having a smooth under face 2 constituting a platen against which the type face of the printing plate is to be straightened. Spaced beneath the heater 1 is the pressure apparatus, not illustrated, but provided with a bed or plate 3. The bed 3 is supported by devices adapted for moving the bed toward the heater 1, and such devices may be any appropriate press mechanism. It has heretofore been the practice to utilize hydraulic or pneumatic pressure for elevating the bed 3 toward the heater 1, but be-

cause of the nature of the present inventions the exactitude of control in the elevation of the bed 3 incident to hydraulic pressure is not absolutely prerequisite, and, therefore, ordinary jacks, or other pressing mechanism, may be employed so long as capable of easy and quick release for lowering the bed 3 instantly or substantially instantly when required.

Mounted on the bed 3 is a spring mat 4 made up preferably of a series of interlaced coiled springs 5, 5. Each spring 5 is a helix making up a cylindrical body and arranged with the longitudinal axis of the cylinder parallel or substantially parallel to the under face of the heater 1 and the upper face of the bed 3. In Figures 3, 4 and 5, the said springs are shown in detail on an exaggerated scale, and are seen to be interlaced to form a continuous, flat mat. The mat will be of a size slightly greater than the back of the type plate which is seen at 6. It will be observed from Figure 5 that the upper face of the mat made up of the springs 5 is formed with a series of longitudinal valleys 7, 7, one between each two springs 5 incident to the contour of the springs, and it is desirable that the proportions of the springs 5 and the number of springs employed shall be such as to reduce the valleys 7 to a minimum in depth and width. Each spring, as illustrated in Figure 5 is laced into the next adjacent spring at each side. The lacing of the springs, however, may be done in such a way as to increase or decrease the number of springs utilized, or the mat 4 may be made in different ways, one of which is hereinafter described with respect to Figures 8 to 10 inclusive. The manner of construction of the mat is, therefore, susceptible of a wide range of variation so long as the general principle is adhered to of presenting a series of resilient, independently-acting points or small areas to the under face of the type plate, which points or small areas are sufficiently juxtaposed to effectively act and stress the material of the plate into motion where motion of such material is necessary for straightening purposes, while other adjacent areas remain unmoved.

The plate 6 to be straightened is mounted on the mat 4, while the bed 3 is in a lowered position (not illustrated), and a sheet of flexible material 8, such as relatively thin cardboard or the like, is interposed between the mat 4 and the back of plate 6. This interposition may be accomplished, as a matter of facility, by the placing of the sheet 8 on the mat before the plate 6 is introduced. The sheet 8 may be of any appropriate flexible material, and is utilized particularly for the distributing of stresses from the otherwise contacting points of the coils of the mat 4. The type metal of plate 6, when softened by heat, would be liable to allow the

several coils of the mat 4 to express their upward spring stress by embedding themselves in the type metal without adequately moving the mass of metal above for straightening the type face, if the sheet or some other appropriate stress distributing element were not interposed between the uppermost point of the coils of the mat 4 and the plate 6. The sheet 8 thus reduces the depth of indentations formed in the back of plate 6 without, however, interfering with the independent and individual expression of stress of each individual loop of the mat 4 when such expression is possible incident to the condition of the type face of plate 6.

In the carrying out of the process after the parts have been assembled by the placing of the mat 4 on the bed 3 in its lowered position, the placing of the sheet 8 on the upper surface of the mat 4, and the placing of the plate 6 on the sheet 8, the bed 3 is raised, by whatever pressure mechanism is utilized for operating it, until the type face of plate 6 comes in contact with the smooth surface 2 of the heating element 1, and then the bed 3 is moved upward a slight distance farther so as to slightly flatten the helices of the mat 4. Thus the plate 6 is held tightly against the smooth face 2 under a stress constantly urging the plate 6 toward the heating element 1 and under conditions such that all of the myriads of independent areas of plate 6 are independently and resiliently stressed toward the heating element. The operator watches the mat 4, after the parts are brought to the position last stated, for any manifestation of an expansive expression of the helices of the mat. The heater 1 may be a gas burner or electrical apparatus, or other heat delivering unit, and is, of course, maintained hot enough to cause the heat units to pass through the copper face of plate 6 and to soften the type metal making up the major portion of the plate 6. Just as soon as the said type metal is sufficiently soft, the individual helices of the mat 4 will expand to their normal round condition or to a condition as nearly approaching a circle as may be possible, and this expression or movement results in the upward movement of any lowered sections or areas, such as seen at 9, 9, of the type face of plate 6. The moment the type metal of plate 6 is soft enough to allow the said movement of the type face to the rectified position, that is to the position contacting uniformly with the smooth surface 2, and such movement is consummated, the parts assume the position seen in Figure 2, and that moment the pressure of the mat 4 should be released. The operator, seeing the slight movement of various coils of mat 4, immediately lowers the bed 3 so as to relieve pressure from plate 6 and avoid any oozing of molten type metal. The straightening process will thus have

been completed so far as the straightening of the face of the plate 6 is concerned, and it is, of course, well understood that the back of plate 6 must be planed or otherwise prepared to adapt the plate for printing purposes just 70 the same as has been commonly done after the type face of type plates have been straightened manually.

The motion of various coils of the mat 4 may be comparatively easily observed by the operator and the bed 3 lowered at the proper and appropriate time, but it is liable to be found that the operator must stoop down, or get into an awkward position, to be able to effectively watch the action of the mat 4. 80 To obviate this necessity, an indicator may be utilized, such as shown in Figures 6 and 7, in which the identical parts above described bear the same reference numerals. To the bed 3 is detachably fixed a bracket 85 10 having an upstanding arm 11, preferably terminating in a tapered edge adapted to serve as a fulcrum. A rod 12 is inserted into any one of the coils 5 and allowed to rest on the fulcrum 11, so that the inner end 90 portion of the rod will be influenced by movement of some of the coils, and such movement may be readily observed by the operator without stooping or otherwise placing himself in an awkward position. Preferably the rod 12 carries at its inner end a plate 13 having ears 14 between which the rod 12 extends. The ears 14 are connected by a pin 15 which is pivotally engaged by the rod 12, as by having the rod looped about 100 the pin 15 and extended beyond the same. The plate 13 is thus free to oscillate slightly relative to the rod 12, and may be brought to a position of contact with the inside of the upper part of two of the coils of any one 105 of the springs making up the mat 4. When the bed 3 is moved upward until the coils of mat 4 are slightly flattened, the rod 12 will take the inclined position seen in Figure 6, and when the type face straightens under 110 the stress while the type metal of plate 6 is sufficiently heated, the rod 12 will swing on the fulcrum 11. Under some conditions, it may be swung to the position seen in Figure 7, or it may be swung to a greater or less 115 extent to other positions, but it will have some movement when the relaxing of some of the helices of the mat occurs. To increase the visibility of this movement, the rod 12 may be substantially lengthened, and the 120 rod is preferably provided with a weight 16 for insuring maintenance of the plate 13 against the inner parts of the particular helices engaged.

The indicating device thus made up of 125 the rod 12 and its engaged and co-operating parts facilitate observation with precision of the time when the bed 3 should be lowered.

In Figures 8, 9 and 10, I have illustrated 130 a slightly modified embodiment of the detail

4 construction of the mat 4. The mat made up of the coil springs, as seen in Figures 3, 4 and 5, requires all of the springs to be unidirectional, since they are screwed together in being interlaced. In other words, they must be either all righthand springs or all lefthand springs, but in the structure seen in Figures 8, 9 and 10, I preferably employ alternate right and lefthand springs, and instead of screwing them together, they are merely interlaced by being pressed together laterally, as best seen in Figure 8 in which the springs 5', 5", are righthand springs while spring 5'' is a lefthand spring. Since the springs 5' and 5'' are not screwed together in being interlaced, means must be provided to prevent separation, and to this end each pair of springs is locked together by the insertion of a rod 17, preferably tubular, between the lapping portions of the helices. Each rod 17 is preferably formed with an appropriate head 18 at one end and a detent 19 at the other, such as a cotter pin or other retaining device for preventing the springs from escaping longitudinally from the rod. Thus the mat made up of the springs 5' and 5'' and rods 17 is more quickly assembled than that of mat 4, but is of slightly greater weight and retains heat to a slightly greater degree incident to the presence of the rods 17. It is, of course, desirable that the mat should not become excessively hot and should not retain an excessive amount of heat.

5 In Figure 11, I have illustrated a coiled spring 20 for use for making up mats in which the wire is of rectangular or square cross section, as seen at 21. This form of wire has a slight advantage over the form seen in the other figures of the drawings, which latter form is the usual cylindrical wire. The square or rectangular wire presents a slightly greater surface at the place of contact and will proportionally reduce the independent indentations in the back of the plate 6. I have, however, experienced no difficulty in this respect in the use of the cylindrical wire springs while the sheet 8 is employed.

51 In Figure 12, I have shown a coiled spring 22 which is flattened, at 23 and 24, its upper and lower portions, for increasing slightly the area of contact, and the idea of this modification corresponds with that of the structure seen in Figure 11 as just described.

52 While the hot process is especially illustrated and described herein, and is preferred for more purposes, I have found that the present inventions are especially well adapted for type plate straightening while cold particularly when the material of the spring mat is sufficiently sturdy and the flexible sheet 8 is duly thickened, as by the substitution of a number of newspapers or the like. It is well also when straightening a plate

while cold to place a flexible cushion, such as newspapers like those just mentioned, between bed 3 and the spring mat in addition to those above the mat. Also, when the cold type plate is straightened, the platen 2 70 may be any appropriate surface whether of the heater or otherwise.

What is claimed is:—

1. In type plate straightening apparatus, the combination, with heating means adapted to be engaged by the face of a type plate, and means for exerting pressure against the type plate toward the heating means, of means interposed between the pressure means and the type plate for delivering the pressure at a series of relatively closely spaced, independently resilient points to the back of the type plate, and a relatively thin sheet of cardboard interposed between the points and type plate for cushioning the distribution of the stress from the points to the plate while leaving effective the independent resiliency of the points.

2. In type plate straightening apparatus, the combination, with heating means, and means for stressing a type plate toward the heating means, of spring coils disposed between the stressing means and the type plate for delivering the stresses resiliently to the type plate edgewise of the coils.

3. In type plate straightening apparatus, the combination, with heating means, and means for stressing a type plate toward the heating means, of spring coils disposed between the stressing means and the type plate for delivering the stresses resiliently to the type plate edgewise of the coils, and a flexible sheet interposed between the coils and the type plate.

4. In type plate straightening apparatus, the combination, with heating means, and pressure means adapted to stress the type plate toward the heating means, of a mat of interlaced springs disposed between the stressing means and the type plate, the springs of the mat being arranged to present relatively closely spaced points toward the type plate.

5. The combination, with type plate straightening apparatus, of a spring mat adapted for delivering straightening stresses to the type plate comprising coiled springs arranged to have the coils presented edgewise toward the plate during a straightening operation.

6. The combination, with type plate straightening apparatus, of a spring mat adapted for delivering straightening stresses to the type plate comprising interlaced coiled springs.

7. The combination, with type plate straightening apparatus, of a spring mat adapted for delivering straightening stresses to the type plate comprising interlaced coiled springs arranged with their longitudinal axes such as to normally lie substantially

parallel to the engaged surface of the type plate.

8. In type plate straightening apparatus, the combination, with heating means, and means for stressing the type plate toward the heating means, of spring means interposed between the stressing means and type plate for delivering the stresses resiliently to the type plate, and an indicator extending beyond the spring means for showing movement thereof when the spring means relaxes incident to type plate straightening movement.

9. A spring mat designed and adapted for use to deliver straightening stresses to type plate comprising curved metallic springs arranged in such contiguity and relation to each other as to present such a succession of relatively closely spaced curved places toward the type plate to be straightened as to effect straightening thereof under sufficient stress, and means for maintaining substantially the stated relation of the springs.

10. A spring mat designed and adapted for use to deliver straightening stresses to type plate comprising coiled metallic springs interlaced and proportioned in size and number of coils to present such a succession of relatively closely spaced curved parts toward the type plate to be straightened as to effect straightening thereof under sufficient stress, and means engaging the springs for restricting relative movement thereof.

11. In the art of straightening type plates, subjecting the face of a type plate to heat, moving spring coils to position for stressing the type plate toward the source of heat under spring pressure edgewise of the coils, and retaining the parts thus tensioned until

the face of the type plate straightens incident to such pressure and heat. 40

12. The combination, with type plate straightening apparatus, of a spring mat adapted for delivering straightening stresses to type plate comprising interlaced springs.

13. In type plate straightening apparatus, the combination, with a platen and pressure means, of a fibrous sheet adapted to engage the back of a type plate contacting with the platen, metallic springs disposed between the pressure means and platen for directly 50 engaging the fibrous sheet and located for delivering stresses from the pressure mechanism to the type plate through said fibrous sheet.

14. In type plate straightening apparatus, the combination, with a platen and pressure means spaced therefrom, of curved metallic springs disposed between the platen and pressure means to deliver stress from the pressure means to a type plate engaging the 60 platen by contact of the curved portions of the springs.

15. In the art of straightening type plates, stressing a type plate toward a straightened condition by pressure exerted through bent 65 metallic springs engaging the plate at the bent portions of the springs.

16. In the art of straightening type plates, stressing a type plate toward a straightened condition by pressure exerted through bent 70 metallic springs engaging the plate at the bent portions of the springs, and cushioning the stress delivered from the springs to the plate.

In testimony whereof I affix my signature.
JOSEPH H. TAYLOR.
